UNITED STATES PATENT OFFICE.

GEORGE E. HULSE, OF NEWARK, NEW JERSEY, ASSIGNOR TO SAFETY CAR HEATING & LIGHTING COMPANY, A CORPORATION OF NEW JERSEY.

SYSTEM OF DISTRIBUTION.

Application filed December 9, 1918. Serial No. 265,823.

To all whom it may concern:

Be it known that I, GEORGE E. HULSE, a citizen of the United States, and a resident of Newark, in the county of Essex and State of New Jersey, have invented an Improvement in Systems of Distribution, of which the following is a specification.

This invention relates to electrical systems such as are employed on railway cars.

One of the objects of this invention is to provide a simple system of the above type which shall be thoroughly dependable in use.

Another object is to provide a practical and efficient system of the above type in which the battery is effectively protected against overcharge.

Other objects will be in part obvious and in part pointed out hereinafter.

The invention accordingly consists in the features of construction, combination of elements and arrangements of parts which will be exemplified in the construction and arrangement hereinafter set forth, and the scope of the application of which will be indicated in the following claims.

In the accompanying drawings wherein I show one or more of various possible embodiments of the several features of this invention, Fig. 1 is a diagrammatic view of a system, and

Fig. 2 is a view similar to Fig. 1 of a modified system.

Fig. 3 is a similar view of another modified system.

Similar reference characters refer to similar parts throughout the different views of the drawings.

Referring now to Fig. 1 of these drawings, there is shown a generator 1, of the type ordinarily employed for railway battery charging and lighting systems and preferably driven from a car axle. This generator is provided with a shunt field 2, and is preferably regulated by a carbon pile regulator 3, comprising the carbon pile 4, the resistance of which is controlled by a voltage coil 5, which operates a lever 6, governing the compression of the pile elements, and a current coil 7 which controls a lever 8, also adapted to govern the compression of the pile elements under certain conditions.

The detailed action of this regulating is not of interest herein but it may be noted

that the voltage regulating coil being always 55 in action, limits the voltage of the generator and thus in itself is adapted to protect the battery as it restricts the generator voltage to a value lower than that which would be required to force a harmful current through 60 a charged battery. It is to be understood that although this regulator is my preferred form, other types of regulation may be employed to advantage.

Mains 9 and 10 lead from the generator 65 terminals, the main 10 including a main switch 16 preferably of the automatic type. The details of this main switch are not shown as my invention does not reside in the specific construction of this switch. It 70 may simply be noted that the function of this switch is to close the circuit of main 10 so as to permit the generator to supply current to the battery and translating apparatus, but to open whenever the voltage of 75 the generator is below that of the battery, thus preventing a discharge of the battery through the generator. From the main switch 16, the main 10 preferably extends through the current coil 7 of the regulator. 80

From series coil 7, main 10 preferably leads to the current coil 11 of an ampere hour meter 12, and from the other end of coil 11 through a switch 13 to storage battery 14, the other terminal of storage battery 14 being connected to the other main 9. It is to be noted that the term "ampere hour meter" is broadly used to denote a device actuated by the flow of charging and discharging current to register substantially the 85 excess of ampere hours put into the battery, and thus the state of battery charge. It is also to be noted that by the expression "register full charge" is meant merely that at full charge the parts will have a predetermined position without respect to the use of a dial or other visual indicating means.

Shunted about switch 13 I provide current-resisting means in the form of asymmetric cell 15, commonly known as an electric valve. This cell is preferably of the iron aluminum type and is so connected as to permit relatively free passage of current in the direction of the arrow indicated thereon, but to greatly impede the passage of current in the opposite direction. It is to be understood that the term "current-resisting means" is used broadly to define any element

or device adapted to resist or impede the flow of an electric current.

Switch 13 is preferably urged to closed position by a spring 17 or other similar means.

- 5 The opening of this switch is controlled by an electro magnetic coil 18, one terminal of which is connected to the main 9 as shown at 19, on the side of the battery remote from the generator, and the other terminal of 10 this coil is preferably connected to the main 10 as shown at 20, between the generator 1 and the main switch 16. It is thus energized by shunting through it a small fraction 15 of the generator current.
- 15 The circuit of coil 18 is normally open, but is adapted to be closed by the action of the switch 21 controlled by the registering hand or other part of the ampere hour meter 12.

- 20 The lead connected at 20 conducts current to the pivot 22 of switch 21, and the lead connected at 19 terminates at a contact point 23 in the path of switch 21.

The contact 23 is so disposed as to be in 25 engagement with switch 21 when the ampere hour meter registers full charge of the battery.

Lamps as at 24 are connected across the mains 9 and 10 in the well known manner 30 in parallel with the battery.

In operation, switch 13 is normally closed. After the car is set into motion at a substantial speed so as to cause the generator 1 to produce a sufficiently high voltage, main 35 switch 16 closes and the generator will supply charging current to the battery through main 10, main switch 16, regulator coil 7, series coil 11 of the ampere hour meter, switch 18, battery 14 and back to the generator through main 9. In parallel with the charging circuit, the generator may also feed current to the lamps 24 connected across the mains.

In the process of battery charge, the ampere hour meter 12 will measure the charge supplied to the battery, and when the battery is fully charged, switch 21 will close upon contact 23, thus closing the circuit of coil 18 across the generator, in parallel with 50 the battery.

The above circuit is closed through the following path:

From the generator lead 10 to the point 20, switch 21, contact 23, coil 18 and point 55 19, thence back to the generator through the lead 9.

If the generator be assumed to tend to overcharge the battery, with switch 21 closed, coil 18 will cause switch 13 to open.

60 The asymmetric cell is thereby connected directly in the battery branch in the path of the battery charging current, and will in view of its inherent properties materially and relatively abruptly reduce the current 65 that can be conducted from the generator to

charge the battery. The battery is thereby effectively protected against overcharge.

In practice, the coil is preferably so constructed as to open when the generator is tending to overcharge the battery and to remain open during such condition. As long as the car is running at a relatively high speed, the switch 13 will therefore remain open and the battery will be protected against excessive charge from the generator. 71 As soon, however, as the car slows down materially, main switch 16 will open, disconnecting the battery from coil 18. The generator will remain connected with coil 18 even after the main switch 16 has opened, 76 but as the speed slows down further, the coil will be weakened until it is insufficiently energized to hold switch 16 in open position. Spring 17 will thereupon close the switch, thus providing a direct connection 81 from the battery to the lamps.

If during this action the lamps 24 are in use, there will be a period between the time of opening of the main switch and the time of closing of the switch 13, in which lamp current would fail were it not for the asymmetric cell 15. The latter however freely permits the flow of discharge current from the battery to the lamps and thus the latter are supplied during this usually brief period of transition. Thus upon failure of the generator to supply the lamps, the battery is immediately effective for this purpose, and it is noted that there will be no momentary dimming of the lamps 24 in 96 causing shift from the supply of lamp current from the generator to supply from the battery.

It will thus be seen that there are provided two independent means for protecting the battery, this independence being of especial value inasmuch as the total failure of one of these means does not prevent protection of the battery by the other.

In Figure 2 I have shown a modified form 11 of my invention, generally similar to that shown in Figure 1 and generally similar in operation. Similar parts are designated by the same reference numerals as in Figure 1, except that certain numerals are primed. The main difference between Figure 1 and Figure 2 is that instead of the asymmetric cell 15 in Figure 1, I employ a resistance 15' for the purpose of reducing the battery charge. The action of the resistance is to 12 materially cut down the charging current when the ampere hour meter registers full charge and a sufficient voltage is impressed across the coil 18'. Another feature of difference between these systems is that whereas in that first described, the coil or magnet 18 is preferably provided with a fixed core acting upon an armature, the corresponding coil in Figure 2 preferably acts upon a movable core pivotally connected with the cir- 13

cuit-controlling member. This core, after the switch has opened, does not require so great a fall in the energizing current to permit closing of the switch as in the system 5 first described, and the parts are so constructed that upon the current in the coil 18' in this latter system falling to a value corresponding to a generator speed which will be just insufficient to harmfully overcharge 10 the battery, the spring will overcome its attraction and recomplete the original circuit of the battery branch.

In Figure 3 is shown a modified type of system in which the general connections of the 15 generator, regulator and lamps are identical with those of the systems hereinbefore described, and are indicated by the same reference characters. The method of protecting the battery by means of the ampere hour 20 meter, however, is somewhat different. The switch arm 13 swings between stops 25 and 26 respectively limiting its movement in the circuit-closing and circuit-opening directions. Bridged about this switch is a motor 27 having in series therewith a resistance element 25 28. This motor is connected to swing the switch member 13 by means of the friction rollers 29 and 30; one direction of drive of the motor throwing the switch into open position, and the opposite direction of drive 30 causing the switch to close its circuit. The field of this motor comprises a continuously connected shunt coil 31 bridged across the mains, and a more powerful differential coil 35 32 the circuit of which is controlled by the switch 21 of the ampere hour meter 12, as hereinbefore described.

In operation, the field 31 normally causes 40 the motor to turn in such direction as to throw the switch arm 13 into circuit-closing position, indicated in dotted lines. When however the ampere hour meter switch has closed the circuit of the more powerful differential field coil 32, the latter in effect 45 reverses the polarity of the motor, causes it to rotate in the opposite direction, and opens switch 13; thus substantially stopping the charge to the battery by reason of the heavy resistance 28. If now the generator slows 50 down or stops and the lamps be turned on, the current from the battery will flow in a reverse direction through the motor 27 to the lamps. This will immediately reverse the direction of drive of the motor, throw 55 the switch 13 into circuit-closing position, and permit the lamps to be freely supplied from the battery. When the generator again comes up to speed, the current will again be reversed through the armature of the motor, 60 and if the ampere hour meter has maintained the circuit closed through field coil 32, the motor will again be reversed and the switch 13 opened.

Although the embodiments shown in Figures 2 and 3 have their special benefits in

use, it is to be understood that the embodiment shown in Figure 1 is in this application more specifically dealt with.

It will thus be seen that there is herein described a method and apparatus for carrying out the method, in which the several features of this invention are embodied, which method and apparatus in their action attain the various objects of the invention and are well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

I claim as my invention:

1. In a system of the character described, in combination, a generator, a storage battery adapted to be charged thereby, an ampere hour meter connected to measure the state of charge of said battery, lamps adapted to be connected with said generator in parallel with said battery, means rendered operative by said ampere hour meter upon full charge of said battery adapted to reduce the charging current passing through the battery branch and permit the flow of current from said battery while said means is in operative condition, and an automatic switch adapted to disconnect said generator, 95 said means being connected with the charging circuit on the generator side of said automatic switch.

2. In a system of the character described, in combination, a generator, a storage battery adapted to be charged thereby, lamps connected with said generator in parallel with said battery, a current resisting device in the battery branch, an ampere hour meter connected to register the state of charge of said battery, means connected with said ampere hour meter adapted to render operative said resisting means upon full charge of said battery, and an automatic switch adapted to disconnect said generator, 105 said last means being connected with the charging circuit on the generator side of said automatic switch.

3. In a system of the character described, in combination, a generator, a storage battery connected to be charged thereby, regulating means for said generator, an ampere hour meter adapted to register the state of charge of said battery, and voltage responsive means connected with said ampere hour meter and rendered operable thereby upon said meter registering full charge of said battery to act independently of said regulating means and upon the attainment of a voltage corresponding substantially to full 125 130

charge voltage to reduce the charging current to said battery.

4. In a system of the character described, in combination, a generator, a storage battery connected to be charged thereby, regulating means for said generator, an ampere hour meter adapted to register the state of charge of said battery, voltage responsive means connected with said ampere hour meter and rendered operable upon said meter indicating substantially full charge of said battery adapted to act independently of said regulating means and to reduce the charging current to said battery upon the attainment 10 of a voltage corresponding substantially to full charge of said battery, and lamps adapted to be connected with the generator in parallel with said battery, said current reducing means acting upon the battery 15 branch.
5. In a system of the character described, in combination, a generator, a storage battery connected to be charged thereby, and a plurality of independent means each of 20 which independently of the other is adapted to reduce the charging current upon said battery reaching full charge, one of said means including a voltage responsive coil connected to register charging voltage and 25 an ampere hour meter connected to register full charge of said battery and to affect the operation of said voltage responsive coil upon said meter indicating full charge of 30 said battery, and the other of said means including and being controlled by a voltage responsive coil connected to register charging 35 voltage.
6. In a system of the character described, in combination, a generator, a storage battery connected to be charged thereby, a plurality of independent means each of which independently of the other is adapted to reduce the charging current upon said battery reaching full charge, an ampere hour meter 40 connected to register full charge of said battery, a voltage coil connected to register charging voltage and to be affected by said ampere hour meter, and another voltage coil connected across the generator, one of said 45 means being controlled by said last-mentioned voltage coil and acting upon the field of said generator and the other of said means being controlled by said ampere hour meter and said first-mentioned voltage coil and 50 acting upon the external circuit.
7. In a system of the character described, in combination, a generator, a storage battery connected to be charged thereby, an automatic switch adapted to disconnect said 55 generator upon said generator slowing down, an ampere hour meter connected to register full charge of said battery, lamps adapted to be connected with said generator, current-resisting means adapted to be connected in the battery branch, means con- 60 trolled by said ampere hour meter adapted to render said resisting means operative upon said battery attaining full charge, and means adapted upon said generator slowing down to act independently of said ampere hour meter and of said automatic switch in rendering inoperative said resisting means.
8. In a system of the character described, in combination, a generator, a battery adapted to be charged thereby, lamps adapted to 65 be connected with said generator in parallel with said battery, an ampere hour meter connected to register full charge of said battery, an automatic switch adapted to disconnect said generator upon said generator slowing down, a coil connected across the charging mains to have its circuit completed by said ampere hour meter upon full charge of said battery, said coil being disconnected from said battery upon said automatic switch opening, and means controlled by 70 said coil and acting upon the battery branch, adapted to reduce the charging current flowing therethrough upon the circuit of said coil being completed by said ampere hour meter.
9. In a system of the character described, in combination, a generator, a battery adapted to be charged thereby, lamps adapted to be connected with said generator in 75 parallel with said battery, an ampere hour meter connected to register full charge of said battery, an automatic switch adapted to disconnect said generator upon said generator slowing down, a coil connected across the charging mains to have its circuit completed by said ampere hour meter upon full charge of said battery, said coil being disconnected from said battery upon said automatic switch opening, and means controlled by 80 said coil and acting upon the battery branch, adapted to reduce the charging current flowing therethrough upon the circuit of said coil being completed by said ampere hour meter.
10. In a system of the character described, in combination, a generator, a battery adapted to be charged thereby, lamps adapted to be connected with said generator in 85 parallel with said battery, an ampere hour meter connected to register full charge of said battery, an automatic switch adapted to disconnect said generator upon said generator slowing down, a coil connected across the charging mains to have its circuit completed by said ampere hour meter upon full charge of said battery, said coil being disconnected from said battery upon said automatic switch opening, and means controlled by 90 said coil and acting upon the battery branch, adapted to reduce the charging current flowing therethrough upon the circuit of said coil being completed by said ampere hour meter.
11. In a system of the character described, in combination, a generator, a battery adapted to be charged thereby, lamps adapted to be connected with said generator in 95 parallel with said battery, an ampere hour meter connected to register full charge of said battery, an automatic switch adapted to disconnect said generator upon said generator slowing down, a coil connected across the charging mains to have its circuit completed by said ampere hour meter upon full charge of said battery, said coil being disconnected from said battery upon said automatic switch opening, and means controlled by 100 said coil and acting upon the battery branch, adapted to reduce the charging current flowing therethrough upon the circuit of said coil being completed by said ampere hour meter.
12. In a system of the character described, in combination, a generator, a battery adapted to be charged thereby, lamps adapted to be connected with said generator in 105 parallel with said battery, an ampere hour meter connected to register full charge of said battery, an automatic switch adapted to disconnect said generator upon said generator slowing down, a coil connected across the charging mains to have its circuit completed by said ampere hour meter upon full charge of said battery, said coil being disconnected from said battery upon said automatic switch opening, and means controlled by 110 said coil and acting upon the battery branch, adapted to reduce the charging current flowing therethrough upon the circuit of said coil being completed by said ampere hour meter.
13. In a system of the character described, in combination, a generator, a battery adapted to be charged thereby, lamps adapted to be connected with said generator in 115 parallel with said battery, an ampere hour meter connected to register full charge of said battery, an automatic switch adapted to disconnect said generator upon said generator slowing down, a coil connected across the charging mains to have its circuit completed by said ampere hour meter upon full charge of said battery, said coil being disconnected from said battery upon said automatic switch opening, and means controlled by 120 said coil and acting upon the battery branch, adapted to reduce the charging current flowing therethrough upon the circuit of said coil being completed by said ampere hour meter.
14. In a system of the character described, in combination, a generator, a battery adapted to be charged thereby, lamps adapted to be connected with said generator in 125 parallel with said battery, an ampere hour meter connected to register full charge of said battery, an automatic switch adapted to disconnect said generator upon said generator slowing down, a coil connected across the charging mains to have its circuit completed by said ampere hour meter upon full charge of said battery, means adapted to disconnect said coil from said battery upon said automatic switch opening, and means controlled by 130 said coil and acting upon the battery branch, adapted to reduce the charging current flowing therethrough upon the circuit of said coil being completed by said ampere hour meter.

ampere hour meter, said last means comprising an asymmetric cell and a shunt about the same controlled by said coil.

11. In a system of the character described, in combination, a generator, a storage battery connected to be charged thereby, lamps adapted to be connected with said generator in parallel with said battery, an ampere hour meter connected to register full charge of said battery, a current-resisting element and a shunting switch therefor connected in parallel in the battery branch, an automatic switch adapted to disconnect said generator, and a coil connected across the mains on the generator side of said automatic switch and having its circuit controlled by said ampere hour meter and controlling said shunting device.

12. In a system of the character described, in combination, a generator, a storage battery connected to be charged thereby, lamps adapted to be connected with said generator in parallel with said battery, an ampere hour meter connected to register full charge of said battery, a current-resisting element and a shunting switch therefor connected in parallel in the battery branch, an automatic switch adapted to disconnect said generator, and a coil connected across the mains on the generator side of said automatic switch and having its circuit controlled by said ampere hour meter and controlling said shunting device, said resisting element comprising an asymmetric cell connected to oppose the flow of charging current.

13. In a system of the character described, in combination, a generator, a storage battery adapted to be charged thereby, a normally inoperative electric valve, connected between said generator and said battery, means responsive to substantially full charge of said battery to adapt said valve to substantially cut down the charging current and voltage responsive means adapted upon the attainment of substantially full charge voltage of said battery to affect the operation of said last-mentioned means.

14. In a system of the character described, in combination, a generator, a storage battery adapted to be charged thereby, an iron-aluminum cell connected between said generator and said battery, a by-pass around said cell, means responsive to substantially full charge voltage of said battery adapted to remove said by-pass, thereby materially cutting down the charging current and means responsive to substantially full charge indication of said battery adapted to af-

fect the operation of said last mentioned means.

15. In a system of the character described, in combination, a generator, a storage battery adapted to be charged thereby, an asymmetric cell connected between said generator and said battery to resist charging of the latter, an electro-magnetic switch responsive to substantially full charge voltage of said battery normally short-circuiting said cell, and means responsive to full charge of said battery to permit actuation of said electro-magnetic switch upon the attainment of substantially full charge voltage.

16. In a system of the character described, in combination, a storage battery, a charging generator therefor, charging current resisting means, a voltage responsive electro-magnetic switch normally short-circuiting said means, an ampere hour meter connected to measure current to and from said battery, and means controlled by said meter upon registry thereby of full battery charge, to place the coil of said switch in circuit with said generator thereby to permit said coil to open-circuit said resisting means in response to a predetermined voltage.

17. In a system of the character described, in combination, a storage battery, a generator provided with mains for charging the same, a device for disconnecting said generator from said battery when the generator voltage is too low for charging, charging current reducing means between the mains and the battery, a control coil for said reducing means adapted to be connected to said generator on the generator side of said disconnecting device, and means comprising an ampere hour meter connected with said battery for so connecting said coil.

18. In a system of the character described, in combination, a storage battery, a generator for charging the same, an automatic main switch for disconnecting said generator from said battery when the generator voltage is too low for charging, an asymmetric cell, normally inoperative, a control coil for said cell adapted to be connected to said generator on the generator side of said switch, and means responsive to substantially full charge of said battery for so connecting said coil.

In testimony whereof, I have signed my name to this specification this sixth day of December, 1918.

GEORGE E. HULSE.
